US00D879202S

(12) **United States Design Patent** (10) **Patent No.:** **US D879,202 S**
Hornsby et al. (45) **Date of Patent:** **** Mar. 24, 2020**

(54) **VEHICLE TOPPER WITH ROOF MOUNT**

(71) Applicant: **Manufacturing Resources International, Inc.**, Alpharetta, GA (US)

(72) Inventors: **Eric Hornsby**, Alpharetta, GA (US); **William Dunn**, Alpharetta, GA (US); **Doug Bennett**, Alpharetta, GA (US); **Mike Brown**, Woodstock, GA (US)

(73) Assignee: **Manufacturing Resources International, Inc.**, Alpharetta, GA (US)

(**) Term: **15 Years**

(21) Appl. No.: **29/641,645**

(22) Filed: **Mar. 23, 2018**

(51) LOC (12) Cl. **20-02**

(52) U.S. Cl. **D20/10**

(58) **Field of Classification Search**

(57) **CLAIM**

The ornamental design for a vehicle topper with roof mount, as shown and described.

DESCRIPTION

FIG. 1 is a front perspective view of the vehicle topper with roof mount;

FIG. 2 is a front elevation view of the FIG. 1 device;

FIG. 3 is a rear elevation view of the FIG. 1 device;

FIG. 4 is a right side elevation view of the FIG. 1 device;

FIG. 5 is a left side elevation view of the FIG. 1 device;

FIG. 6 is a top plan view of the FIG. 1 device; and

FIG. 7 is a bottom elevation view of the FIG. 1 device;

FIG. 8 is a bottom perspective view of the FIG. 1 device shown with the non-claimed environment removed for clarity; and,

FIG. 9 is a bottom perspective view of the FIG. 1 device. The broken lines illustrate portions of the vehicle topper with roof mount and form no part of the claimed design.

1 Claim, 9 Drawing Sheets
